UNITED STATES PATENT OFFICE.

SAMUEL M. SILVERMAN, OF WILKES-BARRE, PENNSYLVANIA, ASSIGNOR TO W. B. BERTELS & SON CO., INC., OF WILKES-BARRE, PENNSYLVANIA, A CORPORATION OF PENNSYLVANIA.

DRUMHEAD.

Application filed December 30, 1922. Serial No. 609,921.

To all whom it may concern:

Be it known that I, SAMUEL M. SILVERMAN, a citizen of the United States, residing at Wilkes-Barre, in the county of Luzerne and State of Pennsylvania, have invented a new and useful Drumhead, of which the following is a specification.

This invention aims to provide a simple means whereby a closure may be held securely in the head of a can or like receptacle, it being impossible to remove the closure without breaking a seal.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in plan, a device constructed in accordance with the invention; Figure 2 is a cross section on the line 2—2 of Figure 1.

The numeral 1 marks the head of a can, the head including a body 2 having an inwardly projecting flange 3 defining an opening in the head, the head being supplied with an outwardly projecting flange 4 having a marginal lip 5. A shoulder 6 is formed at the juncture between the flange 3 and the body 2.

The numeral 7 designates a closure including a base 8 and a rim 9, the rim being provided with a bead 10. The closure fits 7 closely within the flange 3 of the head 1, the bead 10 being received upon the shoulder 6.

The numeral 11 designates a projection or post having a reduced end 12 extended through the base 8 of the closure 7, the projection or post preferably being located at the center of the base and being held thereon by riveting the end 12 on the base of the closure, as shown at 14. The post 11 has a

transverse opening 15. Arms 16 are connected at their outer ends by pivot elements 17 to the body 2 of the head 1 of the can for swinging movement in a direction at right angles to the axis of the can. At their inner ends, the arms 16 are supplied with openings 18 adapted to receive the post 11. The arms 16 have convexed edges 19 enabling the arms to fit up closely against the flange 4 of the head of the can when the arms are in inoperative position, as shown in dotted line in Figure 1, the arms then resting on the body 2 of the head 1. The arms 16 are resilient so that they may be curved downwardly, as shown at 20 in Figure 2, when the post 11 is received in the openings 18 which are formed in the inner ends of the arms. When the arms 16 are mounted on the projection 11 as shown in solid line in Figures 1 and 2, a seal 21 or other fastening means may be mounted in the opening 15 of the post 11. Then, obviously the arms will be held upon the post, and the closure 7 will be held on the head 1, the arms being secured to the part 2 of the head 1 by the pivot elements 17, and being engaged with the bead 10 of the closure 7, as shown in Figure 2.

What is claimed is:—

1. In a device of the class described, a receptacle head having an opening; a closure for the opening; a projection carried by the closure; and arms pivoted at their outer ends to the head, the arms being supplied at their inner ends with openings for detachably receiving the projection.

2. In a device of the class described, a receptacle head comprising a body having a flange and provided with an opening; a closure for the opening; a projection on the closure; and arms pivoted at their outer ends to the body, the arms being supplied at their inner ends with openings for the reception of the projection, the arms being convexed to cooperate with the flange, when the arms are disposed in inoperative position.

In testimony that I claim the foregoing as my own, I have hereto affixed my signature in the presence of two witnesses.

SAMUEL M. SILVERMAN.
